UNITED STATES PATENT OFFICE

2,352,917

SCREW DRIVER

Gilbert W. Scott, Jacksonville, Ill.

Application February 15, 1943, Serial No. 475,979

1 Claim. (Cl. 81—5.1)

This invention relates to the official class of hand tools and more particularly screw drivers.

The primary object of this invention resides in the provision of a screw driver adapted to tighten and remove both small and large screws from scissors, shears and the like.

Another object of this invention resides in the provision of means adapted to securely retain the screw driver blade in the kerfs of the screws of scissors and the like.

A further object of this invention resides in the provision of means adapted to retain the screw driver blade in various positions relative to its handle.

A still further object of this invention resides in the provision of means adapted to prevent the scissors or the like from slipping from the jaws of the handle.

Among the salient features of this invention is the provision of means whereby the screw driver blade will be firmly in engagement with the screws of scissors and the like for operation thereon under leverage of its supporting handle.

With these and other objects in view, this invention resides in certain novel features of construction and arrangement of elements to be hereinafter more particularly set forth in the specification, illustrated in the accompanying drawing and pointed out in the appended claim and, while this disclosure depicts my present conception of the invention, the right is reserved to resort to such changes in construction and arrangement of elements as fall within the spirit of the invention.

In the accompanying drawing forming a part of this application:

Fig. 1 is a side view of the screw driver.

Fig. 2 is a plan view thereof.

Fig. 3 is a perspective view of the front portion of the screw driver.

Fig. 4 is a perspective view of the screw driver blade per se.

Fig. 5 is a perspective view of the screw driver blade retaining block.

Fig. 6 is a perspective view of the scissor supporting block.

In the present illustration of this invention the numeral 5 designates, in general, a screw driver consisting of a lever 6 herein disclosed in the form of pivoted upper and lower jaws 7 and 8 provided with handles 9 of plier like style and operation. Secured to the opposed surfaces of the aforesaid jaws, as by welding or the like, are hardened steel blocks 10 and 11, the former of which is provided with a central hole 12, regis-

tering with a hole 13 extending through the upper jaw 7, and angularly disposed grooves 14, while the latter of which is provided with a concave upper surface 15 to receive the protruding end of the pivotal screw of a pair of scissors or shears resting on the block 11.

Slidably extending through the aforesaid holes 12 and 13 is an elongated shank 16 formed on a screw driver blade 17 and surrounding the shank 10 is an expansion coil spring 18 which exerts its pressure between the upper surface of the jaw 7 and a head 19 secured to the free end of the shank, said spring acts to retain the inner or upper portion of the screw driver blade in an elected groove 14 of the block 10 so as to dispose the same at different angles relative to the handle.

The aforesaid embodiment is adapted to operate on large screws pivotally connecting the blades of large sizes of scissors, shears and the like and, in order to also utilize the tool in removing and tightening small screws of the smaller sizes of scissors and the like, the structure heretofore set forth is reproduced in smaller size 20 and disposed on the handles of the tool as indicated, in general, by the letter A, a description of which is thought unnecessary as the structure and embodiment thereof is precisely that heretofore set forth.

With a screw driver constructed in accordance with this invention it is simply necessary to dispose a pair of shears between the jaws or handles, according to the size thereof, with the outer or free end of the pivotal screw therein set over the concave surface 15 in the block 11, whereupon, the screw driver blade 17 previously seated in an elected groove 14, is brought in contact with the kerf in the screw and firmly held therein as the jaws 7 and 8 are held closed by the operator 25 grasping the handles 9. With the screw driver blade so held into firm engagement with the screws of scissors, the operator of the tool is enabled to readily remove extremely tight screws from scissors and the like simply by partially rotating the tool on the axis of the screw, it being apparent tightening of the screws is facilitated by reversal of said operation.

Through the instrumentality of a tool of this character, it is apparent pivotal screws of both 30 large and small scissors and the like can be readily operated on without distortion of the kerfs therein and, through the simplicity of construction of the tool, operation thereof by unskilled individuals is permitted.

Having thus described my invention what I

claim and desire to protect by Letters Patent is:
A screw driver comprising, a pair of fork shape pivoted jaws, blocks connecting the free ends of the jaws, one of said blocks having an aperture extending therethrough in axial alignment with the center of the other block and having radially disposed grooves in its inner surface and the other block having a concave upper surface opposed to the aforesaid aperture, a screw driver blade having its base portion extending across 10

said apertured block and seated in opposite grooves therein, a shank formed on the base of the screw driver blade and extending through the aforesaid aperture, an expansion spring surrounding the shank with its inner end bearing on that block having the aperture therein, a head carried by the free end of the shank and bearing against the outer end of the spring, and handles formed on the jaws.

GILBERT W. SCOTT.
